H. E. BAKER

GAUGE

Filed June 4, 1925

UNITED STATES PATENT OFFICE.

HOWARD E. BAKER, OF ROANOKE, VIRGINIA.

GAUGE.

Application filed June 4, 1925. Serial No. 34,953.

To all whom it may concern:

Be it known that HOWARD E. BAKER, a citizen of the United States of America, residing at Roanoke, in the county of Roanoke and State of Virginia, has invented 5 certain new and useful Improvements in Gauges, of which the following is a specification.

My invention relates to gauges for use in 10 marking mortises and tenons in windows, sash, doors and the like.

The object of my invention is to provide a 15 gauge by means of which the material to be marked may be quickly and accurately marked.

Another object of my invention is to so 20 mount the markers as to permit ready adjustment upon their support, and also permit movement from operative to inoperative position in order to vary the number of markings to be made.

In the accompanying drawings wherein 25 one embodiment of the invention is illustrated:

Figure 1 is a plan view of the device;

Figure 2 is a side elevation of the same; and

Figure 3 is a section on the line 3-3 of 30 Figure 1.

Referring more specifically to the drawings 35 5 denotes a rectangular elongated base preferably of wood. Projecting upwardly from the top of the base and centrally and longitudinally thereof is a fin like member 6, on each side of which is a graduated scale 7, the purpose of which will be presently described.

Secured to opposite ends of the base 5 40 by any suitable means (not shown) are plates 8 and 9. These plates extend beyond the side walls of the base and are adapted to adjustably support rods 10, one at each side of the base. Brackets 11, attached to the sides of the base centrally thereof serve 45 as additional supports for the rods 10, while set screws 12, in the end plates 8 and 9 serve to lock the rods in the desired adjusted position. Pins 13 projecting inwardly from the end plate 8 are adjustably secured there- 50 in by set screws 14.

Mounted upon the rods 10 for both swing-

ing and sliding movement are a plurality of markers 15 having rectangular projections 16 formed with flat edges 17 and comparatively sharp cutting edges 18. The flat edges 17 rest upon and are supported by the top of the base 5 when the markers are swung to operative position illustrated in Figure 1 and to the left in Figure 3. The markers may be adjusted longitudinally on the rods 10 by loosening the set screws 19, and when adjusted to desired position the set screws 19 are screwed up to hold the markers in place. Likewise any number of markers may be swung to inoperative position illustrated at the right in Figure 3.

In practice the user having determined the number of markings he wishes to make on a door, board or the like, the desired number of markers will be locked in full 70 line, Figure 1 position, opposite a predetermined point on the scales 7. The article to be marked will then be laid upon the cutting edges of the markers on one side of the base, with one end against the adjustable 75 stop pin 13. The user then strikes the article to be marked a few blows with a hammer thus causing the markings to be made in an obvious manner.

It will be understood that either side of 80 the gauge may be utilized depending upon the position of the user with respect thereto.

Having thus described my invention what I claim as my invention is:

1. A gauge comprising a base having a 85 scale thereon, markers swingable toward and from said base, projections on said markers resting upon and supported by said base when said markers are swung to operative position, said markers being adjustable longitudinally of said base and said scale.

2. A gauge comprising a base having a 90 scale thereon a rod secured at one side of said base, markers longitudinally movable on said rod and swingable toward and away 95 from said base, said markers having knife edges and flat portions parallel to said knife edges adapted to rest upon and be supported by said base when swung to operative position.

In testimony whereof I affix my signature.

HOWARD E. BAKER.
